UNITED STATES PATENT OFFICE

JULIUS HORWATH, OF CHICAGO, ILLINOIS, ASSIGNOR TO NEWMAN-RUDOLPH LITHOGRAPHING CO., OF CHICAGO, ILLINOIS, A CORPORATION OF ILLINOIS

ADVERTISING NOVELTY STAND

Application filed September 17, 1929, Serial No. 393,209. Renewed September 29, 1930.

The present invention has to do with improvements in advertising novelty stands. The invention relates especially to improvements in animated display stands in which provision is made for causing a movement of the display matter, or a portion thereof, in such manner as to emphasize the attractiveness of the display and commanding a greater degree of attention to the same. In connection with the foregoing it is an object of the invention to make provision for animating one portion of the display, for example, that portion which is exhibited through an aperture, in comparison to another portion of the 15 display which is stationary. This relative animation of one portion compared to another will further emphasize and draw attention to the portion which is animated.

Another feature of the invention relates 20 to the provision of means for causing the motion to be produced by the use of a current of air operating against a form of propeller or air motor which constitutes a portion of or is connected to the display which is animated.

In connection with the foregoing, it is an 25 object to provide a motor construction of extremely simple design and arrangement; one which will be very effectively operated on by a relatively small fan conveniently located 30 in proximity thereto; and one which has its blades so arranged that they will most effectively receive the impact and force of the current of air. In this connection, it is a further object to so arrange the parts that a 35 relatively small current of air created by a relatively small fan may be used in comparison to a relatively large air motor, so that the current of air will be directed mainly, if 40 not entirely, against the periphery and blades of the air motor at one side of the pivotal point and without the creation of counter or interfering or obstructing forces on the other side of the pivotal point.

45 A further object of the invention relates to

the provision of an improved detail of construction of the pivotal mounting or bearing upon which the rotating element is mounted. In this connection, the parts are so arranged that the bearing stud is blind at the front 50 end, that is, it does not show through on the display surface, but the bearing stud and pivotal mounting parts are located entirely at the back side of the stand and where they are not exposed to view. A further feature in connection with this pivotal mounting is the provision of a construction which is substantially frictionless and will turn and continue to rotate with a very small impulse or force.

Other objects and uses of the invention 55 will appear from a detailed description of the same, which consists in the features of construction and combinations of parts herein-after described and claimed.

In the drawings,

Fig. 1 shows a front face view of a display 60 stand embodying the features of the present invention;

Fig. 2 shows a back view corresponding 65 to Fig. 1;

Fig. 3 shows a vertical detail section 70 through the bearing and hub arrangement taken on the line 3-3 of Fig. 2, looking in the direction of the arrows, but on an enlarged scale; and

Fig. 4 shows a back perspective view similar to Fig. 2, but with the fan in place for 75 delivering the current of air to operate the device.

In the drawings, I have shown the features of my invention as applied to a display, the front face of which is shown in Fig. 1. As illustrated therein, the invention is shown as applied to a stand including a central panel 6, together with a pair of side wings 7 80 and 8, which are joined to the central panel along the fold lines 9 and 10. The features of the invention are applied to the central panel 6, and it will be understood that the illustration of the side panels is merely by 85 90

way of amplification and for the purpose of more fully illustrating the application of the invention.

The display panel 6 is provided with an aperture 11 at the selected point in the surface of the display, through which aperture a portion of the display material is visible. Thus, in the display illustrated, there is shown a carton 12 from which material is being poured in the well understood manner, the aperture 11 being located beneath said carton.

Behind the aperture 11 is located a rotary display panel 13. This panel is carried upon a stud 14, the inner end of which stud is enlarged to establish a flange 15 which sets against the back face of the panel 6. Said stud is secured in this position by means of a disk 16 having a perforation through which the stud 14 extends, but which perforation is so small as to seat against the flange 15 and thus retain the stud securely in place. The disk 16 overlaps the flange 15 a considerable distance and is glued or otherwise secured to the back face of the panel 6.

The rotary display panel 13 is mounted upon the stud 14, for which purpose the panel 13 is preferably provided with a metal eyelet or the like 17 at the point where it is journaled upon the stud. This will reduce the friction and at the same time will assist in keeping the rotary panel 13 even during its rotation, and will reduce the tendency to wobble.

The back end 18 of the stud is enlarged in suitable manner to retain the rotary panel in place.

Secured to the back face of the rotary panel there is another panel 19 of circular form. This panel 19, before being secured in place, is so cut as to establish a series of wings or blades 20 which are connected to the body portion of the panel 19 by radial fold lines 21. Those sections of the panel 19 which lie between the wings or blades 20 are glued or permanently secured to the back surface of the panel 13, but the wings or blades 20 are only connected along the folding lines 21, so that the wings or blades can be turned out and set at a convenient angle to the plane of the disk 13. For example, they may be set at an angle of substantially thirty degrees. Furthermore, all of the wings or blades face in the same direction with respect to the rotation of the device.

Preferably, the wings or blades 20 are not carried inwardly the full radial dimension of the panel 19, so that there is left a central ring 22 which is uncut and which serves to join the rest of the panel 19 together prior to the time that said panel is secured to the back face of the panel 13.

It will be noted that the wings or blades constitute a propeller or wind motor, so that a current of air striking the back face of the

device in the proper direction will cause the panel to rotate. For this purpose, a small motor-driven fan, such as the fan 23 driven by the motor 24, may be located at a convenient position behind the display and set in such position that the current of air will strike the wings or blades from the desired angle and cause the device to rotate. Preferably, the fan 23 is of relatively small size as compared to the diameter of the wind motor, so that the current of air will strike the blades or wings 20 on only one side of the wind motor, thereby causing the same to rotate without serious interference from the wings or blades at the other side thereof.

It will be noted that the aperture 11 exposes a portion of the front face of the rotating panel 13 to view. The desired display matter may be placed upon the front face of the panel 13 in circular form around said panel, as shown at 25 in Fig. 1, so that as the panel rotates the display matter will be brought successively into view through the aperture. Thus, for example, if the material to be displayed is the name of an advertiser or of a certain brand of merchandise, said name may be written around the periphery of the panel so that it will be brought into view during the rotation of the device. As another illustration, waves of the flames of a fire, or other moving or flickering objects may be beautifully and effectively displayed through the aperture and in comparison to other matter of a stationary nature which is displayed on the front face of the panel 6 at the sides of or around the aperture.

While I have herein shown and described only a single embodiment of the features of my present invention, still it will be understood that I do not intend to limit myself thereto except as I may do so in the claims.

I claim:

1. In a display stand, the combination of a stationary panel having suitable display matter on its front face, a stud secured to and projecting backwardly from the rear face of said panel and located exclusively to the rear of said panel, a circular panel having a central eyelet journaled upon said stud and secured in place thereon, suitable display matter on the front face of said rotary panel located in circular fashion around the same and of a nature to harmonize with the display matter on the front face of the stationary panel, there being an aperture in the stationary panel in position to expose said matter on the rotary panel to view as the panel is rotated, a circular panel secured to the back face of the rotary panel and provided with a series of wings or blades reaching rearwardly from the rotary panel at a substantial angle and connected to the rotary panel on substantially radial lines of fold, all of said wings or blades facing in the same direction of rotation, and means for creating a current of air

against the wings or blades at one side of the device comprising a relatively small motor-driven fan located in position to create a current of air against the wings or blades substantially at one side of the center of rotation only, substantially as described.

2. In a display stand, the combination of a stationary panel having suitable display matter on its front face, a stud secured to and projecting backwardly from the rear face of said panel and located exclusively to the rear of said panel, a circular panel having a central eyelet journaled upon said stud and secured in place thereon, suitable display matter on the front face of said rotary panel located in circular fashion around the same and of a nature to harmonize with the display matter on the front face of the stationary panel, there being an aperture in the stationary panel in position to expose said matter on the rotary panel to view as the panel is rotated, and a circular panel secured to the back face of the rotary panel and provided with a series of wings or blades reaching rearwardly from the rotary panel at a substantial angle and connected to the rotary panel on substantially radial lines of fold, all of said wings or blades facing in the same direction of rotation, substantially as described.

3. In a display stand, the combination of a stationary panel having on its front or exposed face a journal stud secured to and projecting rearwardly from the back face of said panel and located entirely to the rear of the panel, a circular rotary panel journaled upon said stud and having on its front face suitable display matter of a nature to harmonize with and correlated to the display matter on the front face of the stationary panel, the display matter on the rotary panel being located in circular fashion around the same, there being an aperture in the stationary panel in position to expose said display matter of the rotary panel to view as said panel is rotated, and a series of wings or blades secured to and projecting from the back face of the rotary panel and all facing in the same direction of rotation with respect to said panel and reaching rearwardly from the panel at a substantial angle and connected to the panel on substantially radial lines of fold, substantially as described.

4. As an article of manufacture, a device of the class described comprising a stationary panel having on its front face suitable display matter, a stud secured to and projecting rearwardly from said panel, a rotary panel journaled upon said stud and having on its front face suitable display matter of a nature to harmonize and correlated with the display matter on the stationary panel, there being an aperture in the stationary panel in position to expose and display the matter on the front face of the rotary panel, and means for receiving the impulse of a current of air to

rotate said panel, said means comprising a circular disk secured to the back face of the rotary panel and having its central portion continuous, and having around its body portion a series of wings or blades cut from the panel and deflected rearwardly therefrom on substantially radial lines of fold and projecting rearwardly at a substantial angle with respect to the plane of the panel, all of said wings or blades facing in the same direction of rotation of the panel, substantially as described.

JULIUS HORWATH.
